UNITED STATES PATENT OFFICE.

THOMAS L. VEST, OF PARKVILLE, MISSOURI.

ICE-TONGS.

1,253,111.

Specification of Letters Patent. Patented Jan. 8, 1918.

Application filed July 12, 1917. Serial No. 180,175.

To all whom it may concern:

Be it known that I, THOMAS L. VEST, a citizen of the United States, residing at Parkville, in the county of Platte and State 5 of Missouri, have invented certain new and useful Improvements in Ice-Tongs; and I do declare the following to be a full, clear, and exact description of the invention, such as will enable others skilled in the art to 10 which it appertains to make and use the same.

This invention relates to improvements in ice tongs and has for its primary object, the provision of a device of this character which 15 may be conveniently used to lower blocks of ice into a refrigerator without causing the usual bumping of the ice on the bottom of the ice box.

Another object is to provide a device of 20 this character which may be operated in spaces in which the ordinary curved pair of tongs could not be used.

With these and numerous other objects in view my invention resides in the novel features of construction and in the combination and arrangement of the several parts as described in the specification and claimed and clearly illustrated in the accompanying drawings which form a part of this application. 30

Figure 1 is a side elevation of my invention in use;

Fig. 2 is an enlarged edge view thereof;

Fig. 3 is a section on the plane of line 3—3 35 of Fig. 2;

Fig. 4 is an enlarged edge view of one jaw; and

Fig. 5 is an enlarged side elevation of one jaw.

Similar numerals of reference are employed to indicate corresponding parts throughout the several views.

The present embodiment of my invention as illustrated in the accompanying drawings 45 comprises a pair of crossed jaws 1 preferably formed from lengths of iron or the like pivotally connected by a bolt or the like 2 at the crossing point and having their upper short ends 3 connected by a suitable handle 4. The portions of the jaws below 50 the crossing point, diverge outwardly a short distance and then are directed downwardly in normally parallel relation to form straight ends 5.

The lower ends of the straight ends 5 of 55 the jaws are substantially rectangular in

cross-section and bifurcated to form parallel spaced ears 6, each pair being provided with transversely aligned apertures adapted to receive a bolt or rivet 8 upon which is mounted 60 a spur 9 for a purpose to be described. The spurs 9 each comprise a substantially rectangular body having a transverse aperture in which is received the rivet or bolt 8, and an inwardly and upwardly extending tapered portion 10 adapted to bite into a block of ice or the like when it is to be lifted. The central portion is provided on its outer side with an outwardly directed lug 11 which is of substantially one-half the thickness of 70 said portion and is disposed on the lower half as illustrated in the drawing. The lug 11 has its end inclined downwardly and outwardly from its upper edge for a purpose to be hereinafter set forth. 75

Each of the straight portions 5 of the jaws is provided with a pair of spaced guides 12 in the form of substantially rectangular loops or links which are larger than the cross-sectional area of the jaw so that when 80 they are secured in place a space will be left between the outer end of the loops or guide 12 whose function will be described. Slidable in each pair of guides, and in parallel relation with the jaw end 5 is a rod 13 85 whose lower end 14 is beveled downwardly and inwardly to slidably engage the inclined end of the lug 11 to actuate the same and move the tapered end 10 inwardly when the rod is permitted to drop by gravity, said 90 operation moving the spur into operative engagement with the block of ice or the like.

For the purpose of locking the spur in engagement with the block of ice and therefore hold in rods 13 in lowered positions, each 95 straight end 5 is provided with a cam 15 pivoted thereto, said cam having a handle 16 which extends upwardly around the point of juncture of the straight end 5 and the diverging portion of the jaw. The cam 100 15 is adapted to engage the upper rounded end of the rod, and in order that the cam may be held against movement, the handle 16, which is formed of spring metal, is received in a longitudinal groove 17, at the 105 point of juncture of the diverging portion and the straight end of the jaw.

It is readily seen that in use the spurs are moved inwardly and locked in position by the cams 15, whereupon the jaws are 110 separated in the usual manner to engage a block of ice.

When the ice is to be placed in a refrigerator or other receptacle having straight vertical walls, the ice may be lowered to the bottom, and the cams swung on their pivots so that upon upward movement of the tongs the spurs will disengage themselves from the ice. This operation cannot be accomplished with the other forms of tongs because of the curved jaws and the inadaptability thereof to such use.

While I have described the tongs as having each straight jaw provided with the pivoted spur, operating rod and locking cam, it is to be understood that I may use this operating mechanism on one of the jaws only.

From the foregoing description the construction and operation of my improved ice tongs will be understood and it is also to be understood that within the scope of the appended claims numerous changes in the minor details of construction may be made without sacrificing the principal advantages.

I claim:

- 25 1. A device of the class described including a pair of straight jaws, a spur pivotally connected between its ends to the end of one of the jaws, guides on said jaw, a rod slideable in said guides and adapted to drop by gravity to contact one end of the spur to move the other end inward, and a cam pivoted to the jaw to engage the upper end of the rod and lock it against movement.
- 30 2. A device of the class described including a pair of straight jaws, a spur pivotally connected between its ends to the end of one of the jaws, guides on said jaw, a rod slideable in said guides and adapted to drop by gravity to contact one end of the spur to move the other end inward, and a cam pivoted to the jaw at a point adjacent the upper end of the rod, a spring metal handle on said cam, and said jaw having a longitudinal groove in its outer face to receive the

spring handle whereby the rod may be 45 locked against movement.

3. A device of the class described including a pair of straight jaws, having their lower ends bifurcated to form spaced ears, a pair of spurs pivoted intermediate their ends between the ears, each spur comprising a substantially rectangular central portion, an inwardly and upwardly directed tapered extension on said portion, an outwardly extending lug on the lower half of 55 each spur, said lug being of substantially one-half the thickness of the central portion, and having its outer end inclined downwardly and outwardly from its upper edge, and means engaging said lug for actuating 60 said spur and locking it against movement.

4. A device of the class described comprising a pair of crossed jaws having their lower ends bifurcated to form spaced ears, a pair of spurs pivotally connected intermediate their ends to the jaws between said ears, said spurs each comprising a substantially, rectangular central portion, an inwardly and upwardly directed tapered extension on said portion, an outwardly extending lug on said body, said lug having its outer end inclined downwardly and outwardly from its upper edge, guides on said jaws, rods slideable in said guides and adapted to drop by gravity to engage the lugs on the spurs to move the tapered ends inwardly, cams pivoted to the jaws and adapted to engage the upper ends of said rods to lock them against movement and a handle connecting the upper ends of the jaws.

In testimony whereof I have hereunto set my hand in the presence of two subscribing witnesses.

THOMAS L. VEST.
